US00D783586S

(12) **United States Design Patent** (10) **Patent No.:** **US D783,586 S**
(45) **Date of Patent:** **** Apr. 11, 2017**

(54) **MOBILE PHONE**

(71) Applicant: **Samsung Electronics Co., Ltd.**, Suwon-si (KR)

(72) Inventors: **Jisang Park**, Yongin-si (KR); **Kiseong Kim**, Gwangmyeong-si (KR); **Hongku Yeo**, Seongnam-si (KR); **Jin-Hoo Lee**, Seoul (KR); **Jaewoong Chung**, Seongnam-si (KR); **Duyeong Choi**, Anyang-si (KR); **Minhyouk Lee**, Seongnam-si (KR)

(73) Assignee: **SAMSUNG ELECTRONICS CO., LTD.**, Suwon-si (KR)

(**) Term: **15 Years**

(21) Appl. No.: **29/580,154**

(22) Filed: **Oct. 6, 2016**

(30) **Foreign Application Priority Data**

Apr. 14, 2016 (KR) 30-2016-0017736

(57) **CLAIM**

The ornamental design for a mobile phone, as shown and described.

DESCRIPTION

FIG. 1 is a top front perspective view of a mobile phone showing our new design according to a first embodiment; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is a bottom front perspective view thereof.

The broken lines immediately adjacent the shaded areas represent the bounds of the claimed design while all other broken lines are directed to environment and are for illustrative purposes only; the broken lines form no part of the claimed design.

1 Claim, 8 Drawing Sheets
